GAS AND OIL SEPARATOR

Richard A. Werts, Avenal, Calif.

Application August 27, 1934, Serial No. 741,609

5 Claims. (Cl. 183—79)

This invention relates to fluid separating means, and particularly pertains to an oil and gas separator.

In various industries, and particularly in industries concerned with the production of oil, such for example, as the oil flowing from a well, and with which gas is commingled it is desirable to provide some simple means for separating the gas from the oil so that the oil may flow directly to storage tanks, and the gas may be led away through suitable pipes for any desired purpose. It is the principal object of the present invention therefore to provide a device adapted to be interposed in the line of flow of mixed fluids, such for example as oil and gas, and which fluids are to be separated as they flow without material retardation and without requiring the use of any expensive or complicated separating mechanism.

The present invention contemplates the provision of a conduit through which mixed fluids may flow, and within which suitable pressure and centrifugal action is set up and controlled to cause the two fluids to be separated and drawn off through separate conduits.

The invention is illustrated by way of example in the accompanying drawing in which:

Figure 1 is a view in plan showing the apparatus with which the present invention is concerned.

Fig. 2 is a view in side elevation showing the apparatus with which the present invention is concerned.

Fig. 3 is a view in end elevation showing the oil and gas separator as seen at the valve end.

Fig. 4 is a view in transverse section through the structure as seen on the line 4—4 of Fig. 2, and indicates the manner in which the oil and gas operation is brought about.

Referring more particularly to the drawing, 40 10 indicates a reservoir structure which comprises parallel reservoir elements 11 and 12 connected adjacent their opposite ends by connecting compartments 13 and 14. The forward ends of these members are closed. The opposite ends of the 45 members are provided with removable cover plates 15 and 16 respectively. These plates also afford mounting lugs 16 which receive the swinging arms 17 of floats 18, one of which is disposed within each of the reservoir elements 11 and 12. Domes 19 are disposed in the upper walls 50 of these reservoir elements above the floats to allow clearance, and downwardly extending bowls 20 are formed in the lower wall of each of the reservoir elements to provide a sand trap. A 55 bleeder valve 21 is disposed in the bottom of

each bowl so that this may be opened to allow the material entrapped therein to be drained out. The swinging float arms 17 in the reservoir element 11 is pivotally connected to a lever shaft 22 to which a link 23 is pivotally secured. The opposite end of this link is pivotally secured to a lever 24 mounted upon a valve structure 25 by which the outflow of oil is controlled. The valve structure 25 is connected with one tubular leg 26 of a T-shaped pipe fitting 27. The other 10 tubular leg 28 of the pipe fitting 27 carries a valve structure 29 fitted with a valve lever 30. This lever is connected to a link 31 pivotally secured at its opposite end to a lever 32 of float pivot shaft 33. The float pivot shaft 33 is connected 15 with the float lever 17 of the float element 18 which is positioned within the reservoir compartment 12. It will thus be seen that as the floats 18 are affected by the level of accumulated liquid within the reservoir elements 11 and 12, 20 they will operate the valves 25 and 29 to control the outflow of liquid so that the liquid level will remain constant at all times, and so that it will normally stand above the level of the outlet or pipe 34 to which the T-shaped pipe 27 is connected. Mounted above the reservoir structure 10 and in communication with the reservoir elements 11 and 12 is a centrifugal separator coil 35. This coil has an induction connection 36 at one end, and an eduction connection 37 at its opposite end. The coil is in the form of a helix and its longitudinal axis lies in the central vertical plane of the reservoir structure 10. The convolutions of the coil are connected through outlet pipes 38 and 39 with the reservoir elements 11 35 and 12 respectively, as shown particularly in Fig. 4 of the drawing. These outlet pipes communicate through the outer wall of the coil 35 so that the heavier material which would naturally move toward this outer wall during the travel of the 40 mixed fluids through the coil would have a tendency to pass into the pipes 38 and 39, and to be drawn off and separated from such lighter materials as were flowing through the apparatus. In order to insure that the heavier material will 45 be diverted into outlet pipes 38 and 39 baffle members 40 and 41 are erected within the coils and extend part way across the path of flow to form an obstruction for the heavier material and to cause this material to flow into the outlet 50 pipes from which the liquid will drain into the reservoir elements 11 and 12. The configuration of the pipes 38 and 39 may be so made as to readily divert the flow of heavy fluids from the coil and it is preferable that these pipes be so ar- 55

ranged that the direction of flow through them will be substantially tangent to the outer circumferential wall of the coils.

For convenience in moving the separator from place to place skid runners 46 and 47 are disposed beneath the reservoir structure to provide a supporting base.

In operation of the present invention fluid is caused to flow into the separating coil 35 through the induction connection 36. This may be brought about at any desired rate of circulation and under any particular pressure. It will be obvious that the pressure may vary under different conditions, and that as a result the velocity of the fluids through the pipes will correspondingly vary. It will also be understood that particularly when oil and gas are the fluids to be separated conditions will vary so that the proportion of gas to oil will be different. These variable conditions require that the structure shall be maintained under a suitable uniform pressure, and that the liquid may flow off from the separator at a rate which will maintain such uniform pressure. In order to establish proper operating conditions and to control them, the T-pipe fitting 27 has been provided, the outer ends of which are equipped with the valves 25 and 29, and beyond which valves cut off valves 42 and 43 are installed, so that either or both of the connections 26 or 28 may be opened to permit flow therethrough. The floats 18 are so adjusted within the structure as to maintain a constant level of liquid within the reservoir compartments 11 and 12, and to insure that these liquid levels will be maintained irrespective of variation in volume of oil passing through the device. The oil and gas will flow along the convolutions of the helical coil 35 and due to the centrifugal action set up in the flowing fluids the heavier fluids, such for example, as the liquid oil, tend to travel along the outside face of the coil and will thus encounter the openings of outlet ports 38 and 39 and deflecting members 40 and 41. These liquids will then drain into the reservoir compartments 11 and 12 where the level of accumulated liquid will be maintained constant by the floats 18. In the event that the proportion of liquid to gas is relatively small, one of the cut off valves 42 or 43 may be closed, thus insuring the maintenance of a proper level of accumulated liquid within the reservoir structure 10, and a constant pressure of the fluids within the reservoir structure and the coil 35 at all times.

It will thus be seen that the structure here disclosed, while simple in construction, and having relatively few operating parts, provides an oil and gas separator which may be readily interposed in a line of flow of mixed oil and gas, and which will automatically and continuously, regardless of volume and velocity of flow, act to separate the liquids from the gases with which they are mixed.

While I have shown the preferred form of my invention, as now known to me, it will be understood that various changes may be made in the combination, construction, and arrangement of parts, by those skilled in the art, without departing from the spirit of the invention as claimed.

Having thus described my invention, what I claim and desire to secure by Letters Patent, is:

1. A liquid gas separator comprising a helical passageway through which mixed liquids and gases may pass under pressure and in unrestricted flow, a liquid reservoir disposed parallel to the direction of travel of said fluids through the helical

passageway, passageways establishing communication between the helical passageway and said reservoir through the outer walls of the convolutions of said passageway whereby the fluids traveling along and adjacent to said outer walls will be diverted into said liquid reservoir and the uniform fluid pressure will be maintained in the helical passageway and the reservoir, and means for restricting the out flow of liquid from said reservoir to maintain said pressure.

2. A liquid and gas separator comprising a helical passageway through which mixed liquids and gases may pass under pressure and in unrestricted flow, a liquid reservoir disposed parallel to the direction of travel of said fluids through the helical passageway, passageways establishing communication between the helical passageway and said reservoir through the outer walls of the convolutions of said passageway whereby the fluids traveling along and adjacent to said outer walls will be diverted into said liquid reservoir, means for restricting the out flow of liquid from said reservoir to maintain a predetermined fluid pressure therein, and means for automatically maintaining the liquid within the reservoir at a desired contant level.

3. A gas and oil separator comprising a tubular conduit through which mixed gases and liquids have an unrestricted pressure flow, said conduit being in the form of a helix, a passageway through the outer wall of each convolution of said tubular conduit whereby the liquids separated from the gases within the conduit by centrifugal action will be drawn off from the gases in the conduit, a reservoir with which said passageways communicate whereby a uniform fluid pressure will prevail throughout the conduit and said reservoir, an outlet valve for the liquid accumulated within said reservoir, and float means for automatically operating said valve to simultaneously maintain a determined quantity of liquid within said reservoir and a constant fluid pressure within the reservoir and conduit.

4. A gas and oil separator comprising a tubular conduit through which mixed gases and liquids have an unrestricted flow, said conduit being in the form of a helix, passageways connected through the outer wall of each convolution of said tubular conduit whereby the liquids separated from the gases within the conduit by centrifugal action will be drawn off from the gases in the conduit, a reservoir with which said passageways communicate and a restricted outlet from said reservoir, and a float valve actuated by the accumulated liquid within the reservoir to control the same.

5. A gas and oil separator comprising a helical conduit through which mixed gases and oils may flow under pressure, said conduit being disposed with its longitudinal axis substantially horizontal, a closed reservoir beneath said conduit and having passageways separately communicating with the individual convolutions of the coil whereby uniform pressure will prevail throughout the coil and reservoir and whereby the liquids separated from the gases in their flow through the coil will drain into the reservoir, a valved outlet for controlling the flow of liquids from the reservoir, a float within the reservoir, operative means between the float and valved outlet to maintain the liquid at a constant level and the space above the liquid within the reservoir at a constant volume whereby uniform liquid pressure may be maintained throughout the apparatus.
